UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,258,782.

Specification of Letters Patent. Patented Mar. 12, 1918.

Application filed April 26, 1917. Serial No. 164,636.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems, and more particularly to such systems which employ automatic ringing for signaling purposes, and which are provided with trunk lines extending to private branch exchanges, chief operators' 15 desks and like positions.

The object of this invention is to prevent the usual objectionable and disagreeable click in the answering operator's receiver when a call over the trunk to which 20 a source of ringing current is connected is being answered.

In accordance with a feature of this invention, when an operator answers the call, by actuating a listening key, contacts there- 25 of coöperate to directly disable the receiver of an operator's telephone set during the period in which ringing current is being removed, after which a relay is operated to render the receiver operative.

30 This invention is illustrated in the accompanying drawing in which all apparatus is shown in its normal and unactuated condition.

There is shown in the drawing a telephone 35 exchange system containing one embodiment of this invention, and comprising a cord circuit A, located at one section C of a switch-board, and a trunk circuit B extending from this section C to a desk-operator's position 40 D at which there is a signaling device, a listening key and an operator's telephone set. It is believed that this invention will be fully understood from a description of the operation of the system shown in the drawing- 45 ing, and it will be so described.

The operator at section C, desiring to signal the desk operator D, inserts a plug 5 into a jack 6, whereupon lamp 7 will be lighted and relay 8 operated. The operation of relay 8 50 causes the actuation of a ringing relay 9 over a circuit from battery through resistance 10, winding of ringing relay 9, normal contact of relay 11, contact of tripping relay 12, and the closed contact of relay 8 to ground. The 55 operation of ringing relay 9 connects a

source of ringing current 15 to the trunk circuit B, causing the operation of relay 16 over a circuit from the source of ringing current 15 through the winding of tripping relay 12, lower alternate contact of ringing relay 9, ring contacts of the plug 5 and the jack 6, condenser 17, right-hand winding of relay 16, tip contacts of the jack 6 and plug 5, and the upper alternate contact of ringing relay 9 to ground. The operating winding of relay 16 is of high impedance, so that the tripping relay 12 is not actuated when in circuit therewith. Relay 16, upon being energized, attracts its armature and locks up over a circuit from battery through the left- 60 hand winding and contact thereof, and contact 4 of listening key 18 to ground. Upon the actuation of relay 16, lamp 19 is lighted to furnish a signal to the desk operator, and remains lighted until the desk operator actuates listening key 18. The ringing current also remains connected to the trunk circuit until the actuation of the listening key by the desk operator. 70

The desk operator, upon observing the 80 lighted condition of lamp 19, actuates listening key 18, causing the following operations in the order named:

1. Opens contact 4 in the locking circuit of relay 16, causing the release thereof and 85 the effacement of lamp 19.

2. The closure of contact 27, thereby es- 90 tablishing a short-circuit for the receiver 29 of the answering operator's telephone set, which short circuit also includes the nor- 95 mally closed contact 30 of a relay 31.

3. The closure of contacts 32 and 33 connecting the operator's telephone set to and bridging relay 34 across, the tip and ring conductors of the trunk circuit. Tripping 95 relay 12 in the cord circuit A, and relay 34, which is slow operating, thereupon operate. The operation of tripping relay 12 permits the operation of relay 11, which in turn short-circuits and causes the release of ring- 100 ing relay 9. By this time relay 34 had at- tracted its armature, bridging relay 31 across the tip and ring conductors of the trunk circuit so that by the time ringing relay 9 has fully released its armatures, 105 substituting current from the battery in the cord circuit for the ringing current, an energizing circuit for relay 31 is completed. Relay 31 now operates over the energizing cir- 110

peating coil 36, winding of supervisory relay 37, lower normal contact of ringing relay 9, ring contacts of the plug 5 and jack 6, contact 33 of listening key 18, contact of relay 5 34, contact 30 and winding of relay 31, contact 32 of listening key 18, tip contacts of the jack 6 and plug 5, upper normal contact of ringing relay 9, and winding 38 of repeating coil 36 to ground. Relay 31, upon 10 attracting its armatures, completes a locking circuit for itself, which includes contact 39, opens contact 30, which is in the short-circuiting path of the receiver 29, and opens contact 40, disconnecting relay 34 from the 15 trunk circuit.

Since the supervisory relay 37 is in circuit with the relay 31, it operates and places the resistance 10 in parallel with the lamp 7, which is thereby effaced, indicating to the 20 operator at the section or position C that the desk operator D has answered. Relay 34 is also slow releasing, so that during the time that ringing relay 9 is releasing its armatures when for an instant no current is 25 connected to the trunk circuit, the contact of relay 34 will be maintained closed until battery is connected with the trunk. Relay 31, which remains in bridge with the talking conductors of the trunk circuit after ringing 30 current has been tripped, serves as an impedance and holding coil for maintaining the supervisory relay 37 operated.

From the above description it will readily be seen that the system embodying the present 35 invention permits of the tripping of ringing current and the connection of talking current to the trunk circuit while the operator's receiver is entirely out of the circuit, thereby avoiding in the answering operator's receiver the disagreeable clicks usually attending the operation of tripping the ringing current. Since the listening key contact itself establishes the short circuit for the receiver 29, close margins which 45 have been present in circuits of a similar nature heretofore employed are avoided.

What is claimed is:

1. A telephone exchange system comprising a trunk circuit extending from one telephone switchboard to a second board, means at one of said boards for applying ringing current over the trunk to the other board, an operator's telephone set at said other board, a switch thereat actuated by the operator for connecting the operator's telephone set to the trunk circuit and for disconnecting the ringing current from the trunk, contacts of the switch included in the talking circuit of the trunk and engaged 55 upon the actuation thereof to short-circuit the receiver of the operator's telephone set, and means operating after the removal of ringing current to remove the short circuit from the receiver.

2. A telephone exchange system comprising

ing a trunk circuit extending from one telephone switchboard to a second board, means at one of said boards for applying ringing current over the trunk to the other board, an operator's telephone set at said other 70 board, a switch thereat actuated by the operator for connecting the operator's telephone set to the trunk circuit and for disconnecting the ringing current from the trunk, a short circuit for the receiver of the 75 operator's telephone set established upon the actuation of the switch and including contacts thereof, and means operating after the removal of ringing current to remove the short circuit from the receiver. 80

3. A telephone exchange system comprising a trunk circuit extending from one telephone switchboard to a second board, means at one of said boards for applying ringing current over the trunk to the other board, 85 an operator's telephone set at said other board, a switch thereat actuated by the operator for connecting the operator's telephone set to the trunk circuit and for disconnecting the ringing current from the 90 trunk, contacts of the switch included in the talking circuit of the trunk and engaged upon the actuation thereof to short-circuit the receiver of the operator's telephone set, and a relay operating after the removal of 95 ringing current to remove the short circuit from the receiver.

4. A telephone exchange system comprising a trunk circuit extending from one telephone switchboard to a second board, means 100 at one of said boards for applying ringing current over the trunk to the other board, an operator's telephone set at said other board, a switch thereat actuated by the operator for connecting the operator's telephone set to the trunk circuit and for disconnecting the ringing current from the 105 trunk, a short circuit for the receiver of the operator's telephone set established upon the actuation of the switch and including contacts thereof, and a relay operating after the removal of ringing current to remove the short circuit 110 from the receiver.

5. A telephone exchange system comprising a trunk circuit extending from one telephone switchboard to a second board, means 115 at one of said boards for applying ringing current over the trunk to the other board, an operator's telephone set at said other board, a switch thereat actuated by the operator for connecting the operator's telephone set to the trunk circuit and for disconnecting the ringing current from the trunk, a short-circuiting path for the receiver of the operator's telephone set established upon the actuation of the switch and including a normally closed contact, and means operating after the removal of ringing current to open the normally closed contact. 125

6. A telephone exchange system comprising a trunk circuit extending from one telephone switchboard to a second board, means at one of said boards for applying ringing current over the trunk to the other board, an operator's telephone set at said other board, a switch thereat actuated by the operator for connecting the operator's telephone set to the trunk circuit and for dis-
5 connecting the ringing current from the trunk, a short-circuiting path for the receiver of the operator's telephone set established upon the actuation of the switch, and a relay having a normally closed contact in
10 the short-circuiting path energized after removal of ringing current.

7. A telephone exchange system comprising a trunk circuit extending from one telephone switchboard to a second board, means at one of said boards for applying ringing current over the trunk to the other board, an operator's telephone set at said other board, a switch thereat actuated by the operator for connecting the operator's telephone set to the trunk circuit and for disconnecting the ringing current from the trunk, a source of direct current connected with the trunk circuit
20
25

upon the disconnection of ringing current therefrom, a disabling circuit for the receiver of the operator's telephone set established upon the actuation of the switch, a relay energized over a circuit including the source of direct current, and a normally closed contact in the disabling circuit opened upon the energization of the relay.

8. A telephone exchange system comprising a trunk circuit extending from one telephone switchboard to a second board, means at one of said boards for applying ringing current over the trunk to the other board, a switch at the other board, a relay bridged across the trunk circuit by the actuation of the switch for disconnecting the ringing current from the trunk, an operator's telephone set connected with the trunk and the receiver thereof disabled by the actuation of the switch, and a second relay connected with the trunk upon the operation of the first relay and energized thereover after ringing current is removed to render the receiver operative.

In witness whereof, I hereunto subscribe my name this 25th day of April A. D., 1917.

CHARLES W. KECKLER.
